UNITED STATES PATENT OFFICE.

LELAND L. SPAIN, OF GLENDALE, ARIZONA.

WRENCH.

1,201,521.

Specification of Letters Patent. Patented Oct. 17, 1916.

Application filed May 3, 1916. Serial No. 95,198.

To all whom it may concern:

Be it known that I, LELAND L. SPAIN, a citizen of the United States, residing at Glendale, in the county of Maricopa, State of Arizona, have invented certain new and useful Improvements in Wrenches; and I do hereby declare the following to be a full, clear, and exact description of the invention, such as will enable others skilled in the art to which it appertains to make and use the same:

The present invention is directed to improvements in wrenches, and has for its object to provide a device of this character so constructed that the movable jaw thereof can be quickly adjusted for engagement with nuts of various sizes.

A further object of the invention is to provide a quick acting wrench constructed in such a manner that the user can upon simply pressing upon a finger piece release the movable jaw so that same can be adjusted with respect to the rigid jaw for clamping a nut.

With these and other objects in view, this invention resides in the novel features of construction, formation, combination and arrangement of parts to be hereinafter more fully described, claimed and illustrated in the accompanying drawing, in which:

Figure 1 is a side elevation of the device. Fig. 2 is a top plan view thereof. Fig. 3 is a longitudinal sectional view through the device. Fig. 4 is a sectional view on line 4-4 of Fig. 1. Fig. 5 is a sectional view on line 5-5 of Fig. 1.

Referring to the drawing 1 indicates the handle, said handle consisting of sections 2 and 3, the section 3 having formed upon its outer end a jaw section 4, which is somewhat thicker than the jaw section 5 carried by the section 2. The sections 3 and 2 have formed at their outer ends recesses 6 and 7, which when confronting form a compartment 8, one end of the compartment being provided with a bearing 9, the purpose of which will appear later. The section 3 is provided with a recess 11 which is substantially triangular in shape and has leading

therefrom a groove 13 which has its outer end opening into the recess 7. The groove has formed therein a shoulder 14 which is engaged by one end of the coil spring 15, the other end of which is engaged with the ratchet head 16, said head having one end rounded as at 17 and loosely pivoted in the bearing 9. A finger piece 18 is provided and is loosely pivoted in the recess 11, and has its outer end extended beyond the adjacent side edges of the sections 2 and 3, whereby the side finger piece can be conveniently engaged with the thumb so as to rock the same. A link 19 has one end engaged with the head 16 and its other end engaged with the finger piece 18 whereby when the finger piece is rocked rearwardly the head 16 will be rocked in the chamber, the purpose of which will appear later.

The movable jaw 20 is provided with a shank 21 which is disposed at right angles to the jaw 20 and has one face thereof provided with ratchet teeth 22 which are adapted to be engaged by the teeth of the head 16, thereby holding the jaw 20 in different adjusted positions. The sections 2 and 3 are provided with confronting transverse grooves 23 and 24, respectively, for slidably receiving the shank 21.

From the foregoing description it will be seen that a wrench has been provided which is exceedingly simple in construction and durability, and one which can be quickly operated to permit the movable jaw to be adjusted.

What is claimed is:

A wrench comprising a handle, a chamber formed at the outer end of the handle, a ratchet head loosely pivoted in the chamber, a recess carried by the handle and spaced from the chamber, said chamber and recess being connected by a groove, a shoulder formed in the groove, a coil spring having one end engaged with the shoulder and the other end with the head, a finger piece loosely pivoted in the recess, a link extending through the spring and engaging the head and finger piece, a rigid jaw carried by the outer end of the handle, a movable

jaw having a shank carried thereby for sliding engagement with the handle, said shank having ratchet teeth carried thereby and normally engaged by the teeth of said head, said finger piece serving to withdraw the head from engagement with the shank to permit adjustment of the movable jaw.

In testimony whereof, I affix my signature, in the presence of two witnesses.

LELAND L. SPAIN.
